UNITED STATES PATENT OFFICE.

WILLIAM WURDACK, OF ST. LOUIS, MISSOURI.

COMBINATION SOCKET-SEATING AND FUSE-TESTING BLOCK.

Application filed December 31, 1923. Serial No. 683,653.

This invention relates generally to panel-board systems of electrical distribution and, more particularly to a certain new and useful improvement in combination socket seating and fuse-testing blocks especially adapted for employment in such systems.

So far as I am aware, the locating of a blown fuse upon a panel board as today generally constructed is more or less inconvenient and involves the expenditure of considerable time, work, and labor; and it is the chief object of my present invention to provide means in the form of a combination socket seating and fuse testing block so constructed that the blown fuse of the panel-board may be located quickly and with facility and convenience.

With the above and other objects in view, my present invention resides in the novel features of form, construction, arrangement, and combination of parts hereinafter described and pointed out in the claims.

In the accompanying drawing,

Figure 1 is a fragmental plan view of a panel-board equipped with combination socket seating and fuse-testing blocks embodying my invention;

Figure 2 is a perspective view of one of the blocks illustrated in connection with a fuse-testing device;

Figure 3 is a fragmental inverted plan view of one of the blocks;

Figure 4 is a vertical sectional view of one of the blocks; and

Figure 5 is a plan view of one of the blocks.

Referring now more in detail and by reference characters to the drawing, which illustrates a preferred embodiment of my invention, A indicates the block proper, which is of hard rubber, porcelain, or other insulation and of suitable height and dimensions, having preferably the form and shape best seen in Figure 2.

Formed in the block A and opening upon its one or upper end, is a pair of spaced circular recesses or pockets 1, 1, and disposed centrally at the base of each pocket 1 is an insulation boss or lug 2 integral with block A. Seated in each pocket or recess 1, is a cup-shaped socket-member 3 of copper or other suitable conducting material, the annular or side wall of which is suitably threaded, and the end wall of which is apertured to accommodate the insulation boss 2, as shown, the sockets 3 being adapted to re-

ceive and accommodate fuse-plugs 4 of standard form and construction. As so seated, it will be seen that the sockets 3 are embraced, and the outer faces of their walls 60 concealed, by the block A.

Having its head 5 disposed upon the boss 2 and forming the end or center contact of the respective socket 3, and extending longitudinally through the block A to the lower end thereof, is a preferably threaded pin or bolt 6 adapted for electrical connection upon the lower end of the block A with the terminal 7 of a conductor 8, as best seen in Figures 3 and 4.

Having engagement with the end wall of each socket 3 and threaded longitudinally through the block A also to the lower end thereof, is a pair of suitably elongated screws 9, 9, for detachably fastening the respective sockets 3 to their seats and also, in turn, adapted for threaded electrical connection with the legs 10, 10, of a yoke-shaped terminal 11, having a laterally extending stem 12 adapted for electrical connection 80 with the terminals 13 of conductors 14. Preferably, as best seen in Figure 3, the block A is suitably cut-away or recessed upon its lower end, as at 15, 16, for seating the terminals 7 and 11, respectively.

At and adjacent its upper end, the block A is integrally formed with a pair of spaced lateral enlargements 17, 17, and formed obliquely in each enlargement 17 to open at its one end upon the upper face of the enlargement and at its other end in the pockets 1, are ways or grooves 18, 18, for accommodating the terminals 19, 19, of a circuit-testing device 20 of standard form, the same, as is usual, including a lamp or other signaling 95 member 21 for visually or otherwise indicating the electrical condition of the electrical device being tested.

In use and operation, a plurality of the blocks A are suitably disposed and mounted 100 in the desired electrical arrangement and connection with the conducting bus-bars, not shown, upon a panel-board B and the sockets 3 thereof, in turn, connected in circuit by means of the conductors 8 and 14 with the 105 various translating devices, also not shown, the system being electrically protected by the several fuse-plugs 4 seated in the sockets 3. Heretofore, as stated, in the employment of panel-boards of the type here generally described, considerable difficulty, inconvenience, and consumption of time have been expe-

rienced in locating a blown fuse-plug. With my invention, however, the enlargements 17 and their ways or grooves 18 permit convenient electrical engagement through or in the blocks A of the terminals 19 of the circuit-testing device 20 with the concealed walls of the several pairs of sockets 3, the then completion or non-completion of the test circuit depending upon the condition 10 electrically of the plugs 4 seated in the tested sockets and their electrical condition being at once indicated by energization or non-energization of the signal 21. Thus, in a simple, but most efficient manner, my invention enables the locating quickly, without requiring the removal of the seated fuse-plugs 4, of the blown fuse-plug of the panel, whereby consumption of time, work, and labor and the consequent cost and expense 20 thereof are greatly obviated.

I am aware that changes in the form, construction, arrangement, and combination of the several parts of my new combination socket seating and test-blocks may be made 25 and substituted for those herein shown and described without departing from the nature and principle of my invention.

Having thus described my invention, what I claim and desire to secure by Letters Patent 30 is:

1. In a combined socket-seating and fuse-testing device, an insulation block formed with a pair of spaced pockets, sockets seated in, and having their walls embraced by, the 35 pockets, and terminal-members engaging the sockets and the block for including the sockets in an electrical circuit, the block having normally open ways both opening at an 40 end upon a surface of the block and leading at their opposite ends into the respective

pockets for freely removably accommodating the projection of circuit-testing terminals through the block and into direct engagement with the walls of the respective sockets. 45

2. In a combined socket-seating and fuse-testing device, an insulation block formed with a pair of spaced pockets, sockets seated in, and having their walls embraced by, the 50 pockets, and terminal-members engaging the sockets and the block for including the sockets in an electrical circuit, the block being obliquely provided with normally open ways both opening at their upper ends upon the upper face of the block and leading 55 at their lower ends into the respective pockets for freely removably accommodating the projection of circuit-testing terminals through the block and into direct engagement with the walls of the respective sockets. 60

3. In a combined socket-seating and fuse-testing device, an insulation block formed with a pair of spaced pockets, sockets seated in, and having their walls embraced by, the 65 pockets, terminal-members engaging the sockets and the block for including the sockets in an electrical circuit, and lateral enlargements integral with the block and each provided with an obliquely downwardly disposed normally open way opening at their 70 upper ends upon the upper faces of the enlargements and leading at their lower ends into the respective pockets for freely removably accommodating the projection of circuit-testing terminals through the block and 75 into direct engagement with the walls of the respective sockets.

In testimony whereof, I have signed my name to this specification.

WILLIAM WURDACK.
